CLAIM

The ornamental design for a naso-gastric tube stabilizer, as shown.

DESCRIPTION

FIG. 1 is a front perspective view of a naso-gastric tube stabilizer showing my new design;

FIG. 2 is a front elevation view thereof;

FIG. 3 is a right-end elevation view thereof; the left end elevation view is a mirror image of the same;

FIG. 4 is a rear elevation view thereof; and

FIG. 5 is a bottom plan view thereof.

FIG. 4

FIG. 5
